DESIGN FOR A COMBINED ROTISSERIE AND DISPLAY DEVICE

Cartha Williams, Chicago, Ill.

Application May 8, 1943, Serial No. 110,153

Term of patent 7 years

To all whom it may concern:

Be it known that I, Cartha Williams, a citizen of the United States, and a resident of Chicago, in the county of Cook and State of Illinois, have invented a new, original, and ornamental Design for a Combined Rotisserie and Display Device, of which the following is a specification, reference being had to the accompanying drawing, forming a part thereof, and in which:

Fig. 1 is a perspective view of a combined rotisserie and display device showing my new design; and

Fig. 2 is an elevational view of the opposite side thereof with respect to Fig. 1.

I claim:

The ornamental design for a combined rotisserie and display device, as shown.

CARTHA WILLIAMS.
